(57) **CLAIM**

The ornamental design for an instrument for manipulating reagent droplets as shown and described.

DESCRIPTION

FIG. 1.1 is a front view of an instrument for manipulating reagent droplets, showing our new design;

FIG. 1.2 is a left side view of the embodiment shown in FIG. 1.1;

FIG. 1.3 is a right side view of the embodiment shown in FIG. 1.1;

FIG. 1.4 is a back view of the embodiment shown in FIG. 1.1;

FIG. 1.5 is a top view of the embodiment shown in FIG. 1.1; FIG. 1.6 is a bottom view of the embodiment shown in FIG. 1.1; and

FIG. 1.7 is a perspective view of the embodiment shown in FIG. 1.1.

The claimed design concerns an instrument for manipulating reagent droplets; The key features lie in the appearance of the product; No particular color or shade is claimed.

The broken lines shown in the figures are for the purpose of illustrating portions of the instrument for manipulating reagent droplets and form no part of the claimed design.
